UNITED STATES PATENT OFFICE.

ALONZO LAFAYETTE FOWLER, OF COEUR D'ALENE, IDAHO, ASSIGNOR OF ONE-HALF
TO RAYMOND A. STRUNK, OF COEUR D'ALENE, IDAHO.

EASEL.

Application filed May 4, 1925. Serial No. 27,999.

My invention relates to improvements in easels for supporting displays, signs, small articles of merchandise, and the like, and it consists in the combinations, constructions and arrangements herein described and claimed.

An object of the invention is the provision of an easel which is adapted to be made of pasteboard, light gauge metal, or the like but which by reason of its novel construction will be securely braced and stayed against accidental collapse and will last a relatively long time in the service for which it is intended.

Other objects and advantages of the invention will be apparent from the following description, considered in conjunction with the accompanying drawings, in which—

Figure 1 is a perspective view of a card supported by one form of easel embodying the invention,

Figure 2 is a rear face view of the card with the easel blank attached thereto,

Figure 3 is a view similar to Fig. 2, showing the positions of the sections of the easel blank after the first step of the operation of folding the easel blank has been accomplished,

Figure 4 is a view similar to Figs. 2 and 3, showing in full lines the positions of the sections of the easel blank after the sections have been folded and showing a strip of adhesive tape for retaining the sections folded, extended positions of certain of the sections being shown in dotted lines,

Figure 5 is a section along the line 5—5 of Fig. 1, showing the sections of the easel folded and the flaps of the strip of adhesive tape applied,

Figure 6 is a vertical section through the card and through the supporting easel.

Figure 7 is a perspective view of a modification,

Figure 8 is a face view of the easel shown in Fig. 7 in collapsed or opened out condition.

Figure 9 is a perspective view of another modification,

Figure 10 is a view similar to Fig. 8 of the modification shown in Fig. 9.

Figure 11 is a perspective view of another modification,

Figure 12 is a face view of the easel shown in Fig. 11 opened out,

Figure 13 is a perspective view of another modification,

Figure 14 is a face view of the easel exhibited in Fig. 13 opened out,

Figure 15 is a perspective view of another form of easel embodying the invention,

Figure 16 is a face view of the form of easel exhibited in Fig. 15,

Figure 17 is a perspective view of still another modification, and

Figure 18 is a perspective view of a securing strip which is comprised in the form of easel shown in Fig. 17.

The improved easel is made of a single sheet of blank of pasteboard, light gauge metal or like material. This blank is fashioned and creased or folded along the lines indicated at 1, 2, 3, and 4, respectively in Fig. 2 to provide a substantially rectangular attaching section 5, a pair of triangular bracing side sections 6, and a pair of substantially rectangular bracing outer end or back sections 7. Each section 7 is substantially of the same length and width as the attaching section 5.

The attaching section 5 is secured flatwise to the back of a card 8 by adhesive or in any other suitable known manner so that the lower edge of the attaching section is substantially flush with the lower edge of the card. The card 8 of course represents any display card, sign, small article of merchandise or the like or a means for supporting any small object.

The outer end sections 7 then are bent substantially at right angles to the side sections 6, as shown in Fig. 3. The side sections then are folded along the lines 2 and 3, respectively, until parallel to each other and until the outer end sections 7 are lapped and the free side edge of one of the sections 7 abuts the inner face of the opposite side section 6 adjacent to the line of juncture of said side section with the other end section 7. It will be manifest that the sections of the easel will brace one another against collapse when the sections are held folded in the positions just described and that the lapped outer end or back sections and the attaching section will converge together at

their upper ends, being inclined toward each other. The card 8 therefore will be supported in inclined position when all sections of the easel rest at their lower edges 5 on a flat supporting surface.

A strip of adhesive tape has a body portion 9 secured on the outer of the lapped sections 7 and has an extending upper end flap 10, a lower end flap 11, and a side flap 12 which extends beyond the free side edge of the outer of the lapped sections 7. When the sections of the easel blank have been folded in the manner described, the lower end flap 11 is bent inwardly and upwardly 15 over the lower edges of the lapped sections 7 and is secured against the inner face of the inner section 7. The upper flap 10 is bent upwardly against the card 8 above the upper end of the easel and is secured to the card. 20 The side flap 12 is bent inwardly over the free edge of the outer of the lapped sections 7 onto the outer face of the adjacent section 6, and is secured to the latter.

The strip of adhesive tape just described 25 is only one of a plurality of means which can be employed to hold the sections of the easel folded and I desire that it be understood that any suitable known means can be used without departing from the spirit and scope 30 of the invention to hold the sections of the easel folded.

The modification shown in Figs. 7 and 8 includes an attaching section 13, triangular bracing side sections 14, and a pair of back sections 15. A strip of adhesive has a body portion 16 secured on the back of the outer section 15 so as to have a side flap portion 17 extending beyond the free edge of said outer section 15. A second strip of adhesive 35 is secured on the front face of the attaching section 13 and has an extending upper end portion 18. A third strip of adhesive is secured to the inner face of the inner of the sections 15 and has an extending lower end 40 section 19. The sections of the easel are arranged as shown in Fig. 7 and are secured in set up position by the flaps 17, 18 and 19, the flap 17 being secured to the adjacent side bracing section 14, the flap 18 being 45 folded outwardly and downwardly and secured to the back of the outer section 15 and the flap 19 being bent outwardly and upwardly and secured to the back of the outer section 15.

50 The attaching section 13 can be secured to a card 20 or the like by adhesive or in any other suitable known manner.

The form of the device shown in Figs. 9 and 10 differs essentially from the form of the device shown in Figs. 7 and 8 only in that the bracing side sections, designated 14', of the form of the device shown in Figs. 9 and 10 have bottom wings 21 foldable 55 along their lines of juncture with the side sections 14' from the position shown in Fig.

10 to superposed position, the lower of the superposed bottom wings carrying an adhesive flap 22 foldable upwardly onto the adjacent side section 14' and being adapted to be secured to the latter.

The form of the device shown in Figs. 11 and 12 also is very similar to the form of the device exhibited in Figs. 7 and 8 but differs from the latter principally in that the attaching section, designated 13^a is relatively short and the side sections, designated 14^a have the bottom edges thereof inclined or beveled as indicated at 23. The form of the device exhibited in Figs. 11 and 12 is particularly well adapted for use in supporting cut out displays such as represented by the card 24 in Fig. 11, the beauty of the display not being marred by the extension of the attaching section of the easel below the cut out.

The form of the easel shown in Figs. 13 and 14 is very similar to the form of the device which is illustrated in Figs. 9 and 10 but differs from the latter in that attaching section, designated 13^b, of the form of the device shown in Figs. 13 and 14 is relatively short and the side sections designated 14^b, of the last named form of the device have beveled or inclined bottom edges when the easel is in card or display supporting position as shown in Fig. 13.

The easel shown in Figs. 15 and 16 preferably is made of a light gauge metal although it may be made of any other suitable material. It includes an attaching section 24, triangular side sections 25, back sections 26, and bottom wings 27 at the lower ends of the side sections. The sections are folded to the positions shown in Fig. 15 when the easel is set up. The attaching section 24 has a middle securing tab 28 at its upper end flanked by two other fastening tabs 29. The outer of the back sections 26 has spaced attaching tabs 30 at the free edge thereof. The lower of the bottom wings 27 has an attaching tab 31 at the free edge thereof. The tab 28 is bent outwardly and downwardly onto the outer of the back sections 26. The tabs 30 are bent through apertures 32 in the adjacent side section 25 against the inner face of the inner back section 26. The tab 31 is bent through an aperture 33 in the bottom edge of the adjacent side section 25 onto the inner face of the inner bottom wing 27. A pair of lateral tabs 34 on the attaching section 24 adjacent to the lower end of the latter and the tabs 29 are adapted to be bent forwardly for engagement with slots in a display card, not shown, or the like to secure the display card to the easel.

The sections of the easel shown in Figs. 15 and 16 will be held firmly although releasably in set up position by the means just described.

The easel shown in Fig. 17 may be made

of pasteboard or any other suitable material and includes an attaching section 24^a, triangular side sections 25^a, back sections 26^a, and bottom wings 27^a on the side sections 25^a. A metallic securing strip 35 has tangs 36 secured in the outer back sections 26^a of the easel so that fastening tabs 30^a on the securing strip extend beyond the free edge of outer back section 26^a of the easel.

10 The tabs 30^a are adapted to be bent through apertures 32^a in the adjacent side section 25^a of the easel onto the inner face of the inner back section 26^a of the easel. The lower bottom wing 27^a has spaced fastening tabs 31^a adapted to be bent through apertures 33^a in the adjacent side section 25^a onto the inner face of the inner bottom wing 27^a. The sections of the form of the device shown in Fig. 17 thus will be secured firmly, all 20 though releasably in set up position.

It is to be understood that the invention is not limited to any particular means for holding in set up position the sections of any form of easel which the invention may 25 embody as any suitable means may be used for holding the sections of the easel in set up position either permanently or releasably, as desired.

I claim:

30 1. An easel formed of a continuous sheet of light gauge material and comprising a quadrangular front section, a pair of similar triangular side sections joined to the front section at the lateral edges of the latter,

and quadrangular back members joined to 35 the triangular side sections at the rear edges of said side sections, all adjoining edges being coextensive in length.

2. An easel comprising a quadrangular front section, a pair of triangular side sections joined at their front edges to the side edges of the front section, the adjoining edges being co-extensive in length, said side sections being disposed at right angles to the front section, and a pair of lapped quadrangular back members joined to the rear edges of the side sections, the adjoining edges of the back members and the side sections being coextensive, the upper edge 45 of the front section abutting the upper edges of the back members.

3. An easel comprising a hollow body tapering toward its top, said body being rectangular in horizontal cross section and triangular in vertical section taken on a 50 plane extending through the front and back portions of the body, said body being closed at its top, sides, front and back.

4. An easel made of a single sheet of light gauge material bent to provide a quadrangular front section, a bracing back member comprising a pair of quadrangular lapped lateral portions of said sheet, and bracing 55 triangular side sections staying the front and back members to each other; the joined 60 edges of adjacent sections being coextensive in length.

ALONZO LAFAYETTE FOWLER.
